UNITED STATES PATENT OFFICE.

BENJAMIN J. C. HOWE, OF INDIANAPOLIS, INDIANA.

DEVICE FOR THE CONVERSION OF MOTION.

SPECIFICATION forming part of Letters Patent No. 761,173, dated May 31, 1904.

Application filed August 11, 1902. Serial No. 119,156. (No model.)

To all whom it may concern:

Be it known that I, BENJAMIN J. C. HOWE, a citizen of the United States, residing at Indianapolis, in the county of Marion and State of Indiana, have invented certain new and useful Improvements in Devices for the Conversion of Motion, of which the following is a specification.

The objects of my invention are the conversion of a rotary into reciprocating motion and a reciprocating into a rotary motion, and more especially was my object to attain an extended rectilinear motion from a rotary motion, as the primary purpose in the production of this device was prompted by the necessity of a suitable means for the construction of comparatively light apparatus for the operation of pumps for fire-extinguishing purposes to be equivalent to the more cumbersome pumping machinery of the ordinary type which is met with in that class of work. The necessity of an extended rectilinear motion from an apparently light system of members of rotation was desired, as a piston of small area when reversed at the end of its stroke would affect the column of water issuing from the nozzle in a much less degree than would a piston of large area and that the strokes would be fewer in number than in pumps of ordinary practice, and I attain these objects by means and construction described in the following specification and illustrated in the accompanying drawings, in the different views of which similar characters of reference refer to similar parts, and in which—

Figure 1 is a broken side elevation of my device as applied to a pump. Fig. 2 is a top view of same. Fig. 3 is a vertical sectional end view on line 3 3 looking in the direction of the arrow. Fig. 4 is a detached view of guard mechanism I employ to retain gears in mesh.

a is a reciprocating double rack or oblong gear reciprocating longitudinally between two bearing-uprights on base *b*, extending upwardly to the center of said gear and adapted to support sections of shafts or pins at *b*¹, extending in line with each other and projecting nearly to the said gear. Upon or near inner end of said shafts are mounted shifting or

swinging arms *e*, supporting at outer end a short shaft *e*', on which are mounted the vibrating or shifting gears *g* and *g*', which are represented as being integral, the latter gear, *g*', meshing with the oblong gear-teeth *a*', while the gear *g* meshes with gear *g*², mounted on a shaft *b*⁴ at inner end and which is provided with drive wheel or pulley *b*⁵ at outer end thereof for the driving-belt to drive my device in applications of this class. At *b*² is a projection on one of the said bearing-uprights providing a stationary pivotal point for a shifting guard-link *d* at *b*³, which is at opposite end pivoted to upper end of the upright standard *c* to the axle-pin of the guard-roller *c*', also mounted at this point, said standard *c* being mounted at lower end on the shifting or vibrating shaft *e*' of gear *g*'. Now as the respective ends of the standard *c* are stayed by the link *d* and arm *e*, that it cannot swerve laterally, but being free to move up or down as far as the gear *g*' may move up or down within the oblong gear *a*, as represented by dotted lines *g*' in Fig. 4, as when gear *g*' meshes at point *a*⁵ or at point *a*⁶, a guard rail or bar *a*² being provided; preferably, at top of the gear *a*, over and under which the guard-roller *c*' is adapted to traverse in constant contact with said guard, passing around the end of said guard when inner end of stroke is reached, as seen at *c*' in Fig. 1, or at *c*^a when outer end of stroke is reached, whereby the said gear *g*' is retained in positive mesh with the teeth *a*'. The double rack or oblong gear is provided with a flange projecting on both sides, as at *a*³, and suitable recess or guide at *b*', provided in base *b*, within which said rack is reciprocated operating in connection with gears above described.

f represents a pump-cylinder, the piston-rod of which is connected directly to the gear *a* and firm stay-rods *f*' *f*', connecting between the said cylinder and the bearing-uprights of base *b*, one supporting-gear *g*², which drives the shifting gears that the cylinder may be held firmly.

In operation of my device as applied in this case to a pump the power is applied by belt to the belt-wheel, rotating the gear *g*² in either direction, *g* and *g*' being rotated thereby in reverse direction, the latter engaging with the

teeth of the oblong gear a at alternate intervals, as in this case at the upper side a^5 , then at the lower side a^6 , actuating the oblong-gear casting, the shifting of the said shifting 5 gears being accomplished by means of the constant rotation of the pinion g' , when the arched section of teeth at either end of said oblong-gear is met rising at one end of stroke and falling at the other, the antifriction-roller c being 10 at all times in contact with the guard a^2 , alternately above then below said guard, and as when rotary motion is transmitted to the pinion g' gear-casting a is reciprocated, and when a reciprocating motion is given to said 15 gear-casting a from some external source this motion is in turn converted and results in a constant rotary motion being transmitted through the train of gear-wheels to the belt-pulley.

20 In the application of my device there are alterations that may be resorted to that are within the spirit and scope of my invention, and I would have it understood that I feel at liberty to make any such alterations as fall fairly within such scope, and

25 What I claim as new, and desire to secure by Letters Patent, is—

1. In a device for conversion of motion, an oblong internal gear having rectilinear reciprocating motion, a gear-pinion having rotary motion operating within said oblong gear and meshing continuously with the teeth thereof, arms mounted at each side of said oblong gear at fixed pivotal points at one end and 35 supporting the axle of said pinion at the other end, a guard-rail secured to said oblong gear, a guard-roller controlled by its engagement with said guard-rail and means to support and retain said roller in a position constantly vertical above said pinion substantially as and for the purposes set forth.

2. In a device for the conversion of rotary motion to reciprocating or reciprocating to rotary motion an oblong internally-toothed gear 40 formed as of two parallel racks joined at ends to semicircular internally-toothed arcs pro-

viding a continuous series of teeth, a pinion of a diameter smaller than the space between the racks, swinging arms pivoted at one end to a fixed point and supporting the outer ends 50 of axle of said pinion at their swinging ends, a link equal in length to that of said arms pivoted at one end at a fixed point preferably directly over or above the said pivotal point of said arms and extending parallel with said swinging arms to a swinging pivotal point directly over the axle of said pinion, an upright standard pivoted to said link at the latter pivotal point at upper end and to said axle of said pinion at the lower end, a guard-roller 60 journaled at upper pivotal point of said link and said upright, a guard-rail with which said guard-roller is in constant contact alternately above and below it during continuous rotary motion of said pinion secured to and moving 65 with said oblong gear as set forth.

3. In a device for the conversion of rotary motion, a reciprocating member provided with open center of oblong form, a continuous series of gear-teeth within said center, a rotating pinion whose teeth are adapted to mesh in said gear-teeth the outside diameter of said pinion being smaller than the distance between the points of the teeth on opposite sides of oblong gear so formed, swinging arms pivoted at a fixed point at center of the height of the oblong opening in said reciprocating member and at each side thereof in bearings formed on the base in this case, said pinion mounted in movable ends of said arms, a guard-roller mounted at a point outside of said oblong gear, a guard-rail provided on and moved with said oblong gear adapted to engage said guard-roller and means for transmitting rotary motion to said parts, substantially as set forth.

70 Signed this 26th day of July, 1902.

BENJAMIN J. C. HOWE.
